UNITED STATES PATENT OFFICE.

PETER H. LINDSEY, OF LOCKPORT, NEW YORK.

CAR-WHEEL.

SPECIFICATION forming part of Letters Patent No. 237,398, dated February 8, 1881.

Application filed July 24, 1879.

To all whom it may concern:

Be it known that I, PETER H. LINDSEY, of Lockport, in the county of Niagara and State of New York, have invented new and useful 5 Improvements in Car-Wheels, of which the following is a specification, reference being had to the accompanying drawings.

This invention relates more especially to that class of car-wheels which are used on elevated and street railways; and it has for its 10 object the construction of a light, strong, and non-resonant wheel.

The invention consists, principally, of a car-wheel composed of a recessed metallic disk, a 15 wooden tread having the inner portion of the flange formed with it, and an outer clamping-plate, as will be hereinafter more fully set forth.

In the accompanying drawings, Figure 1 is a 20 front elevation of my improved car-wheel. Fig. 2 is a sectional elevation thereof. Fig. 3 is a front elevation with the outer clamping-plate removed. Fig. 4 is a front elevation of the metallic disk. Fig. 5 is a rear elevation of 25 two sections of the wooden tread. Fig. 6 is a sectional view of the tread of the wheel, on an enlarged scale.

Like letters of reference designate like parts in the several figures.

30 A represents the metallic disk forming the body of the wheel. It is provided at its center with a projecting hub, b, by which the wheel is secured to the axle in the usual manner, and at its circumference with a flange, c, 35 which projects beyond the face of the disk A, so that the latter is depressed or recessed between the flange c and hub b.

d are stiffening ribs or webs connecting the hub b with the flange c on the face side of the 40 disk A.

D represents radial sections, made of some suitable hard wood, and arranged upon the face side of the disk A, between the hub b and flange c of the disk.

45 E is an annular clamping-plate, which surrounds the hub b, and is placed against the outer side of the sections D. The sections D are preferably made tapering from the hub toward the tread, and the disk A and clamping-plate E are made dished or concave on the 50 sides contiguous to the sections D, so as to

form a dovetail groove, which surrounds the hub, and in which the sections D are firmly held, as clearly shown in the drawings.

f are fastening-bolts, passing through the 55 disk A, sections D, and outer clamping-plate, E, for securing these parts together. The bolts f are preferably located at the joints of the sections D, as shown in Fig. 3, whereby the bolts are made to serve at the same time as 60 dowel-pins, and prevent the displacement of the sections in a radial line. The fastening-bolts f are placed at every alternate joint of the sections D, so as not to interfere with the ribs d of the disk A. The circumference or 65 outer circular surface of the sections D is so shaped as to form not only the tread of the wheel, but also the inner portion, g, of the flange, which runs in contact with the rail. By constructing the sections in this manner 70 the outer joint between these sections and the flange c is located at a point where it is not liable to come in contact with the rail, and the chipping or breaking out of the flange in passing over a frog is thereby avoided. By this construction of the sections D an unbroken 75 surface of wood only is brought in contact with the rail, both on the top and side thereof, and the noise produced by the wheel in rolling over the rail is thereby greatly lessened. The two 80 sections D, which are fitted against each rib d, are recessed on their contiguous sides, as shown at h, Fig. 5, to receive and cover the rib d. i ii is a packing composed of sheet-lead, rubber, felt, or some other suitable non-conductor of sound, and arranged, respectively, 85 between the sections D and the disk A, and the outer clamping-plate, E, to prevent the transmission of the sound through the body of the wheel.

The disk A is preferably cast of malleable iron or cast-steel, and its flange b is chilled. The sections D are preferably made of hickory or some similar hard wood.

In order to render the sections D impervious to water and perfectly smooth they are 95 preferably saturated with oil which holds flour of emery in suspension.

My improved wheel is very light and strong, and having its tread and the inner portion of 100 its flange formed of non-resonant material, it is especially adapted for use on elevated and

street railways, where the noise caused by ordinary metallic car-wheels is very objectionable.

My improved wheel is constructed at comparatively small cost, and its sections forming the tread can be readily replaced when worn out.

I am aware that wheels have been made embodying in their construction the broad idea of combining wood and metal to obtain strength and avoid resonance; and I am also aware that in this class of wheels it has been suggested to form the tread of the wheel of wood, and that compound wheels have been provided with noiseless tires, and I do not wish to be understood as making claim to any such broad features of construction; but

I claim as my invention—

1. A car-wheel composed of the disk A, having a flange, c, formed thereon, and projecting laterally beyond the face of the disk, sections D, forming the tread of the wheel, and the inner portion, g, of the flange, and an outer clamping-plate, E, substantially as set forth.

2. A car-wheel composed of the dished disk A, provided with the laterally-projecting flange c, sections D, made tapering from the hub toward the tread of the wheel, and the outer dished clamping-plate, E, substantially as set forth.

3. The combination, with the disk A, provided with the laterally-projecting flange c, projecting beyond its face, hub b, and connecting-ribs d, of the sections D, formed with the annular projecting lip g, and fastening-bolts f, arranged at the joints of the sections, substantially as set forth.

4. The combination, with the disk A, non-resonant sections D, and outer clamping-plate, E, of the packing sheets or plates i i', arranged between the sections D and the disk A, and outer clamping-plate, E, substantially as and for the purpose set forth.

PETER H. LINDSEY.
